UNITED STATES PATENT OFFICE.

AXEL C. V. MALM, OF DAYTON, OHIO, ASSIGNOR TO THE EGRY REGISTER COMPANY, OF DAYTON, OHIO, A CORPORATION OF OHIO.

MACHINE FOR PERFORATING WEBS OF PAPER.

1,287,066.

Specification of Letters Patent. Patented Dec. 10, 1918.

Application filed February 7, 1916. Serial No. 76,504.

To all whom it may concern:

Be it known that I, AXEL C. V. MALM, a citizen of the United States, residing at Dayton, in the county of Montgomery and State of Ohio, have invented certain new and useful Improvements in Machines for Perforating Webs of Paper, of which the following is a specification, reference being had therein to the accompanying drawing.

This invention relates to mechanism for perforating a web or webs of paper, metal, cloth or like material. It is particularly adapted for use in connection with printing presses for perforating the paper either before or after it has been printed. The invention may be utilized for making a single series of perforations or any number of perforations in any order or location.

It has been found to be a matter of great difficulty in perforating paper to secure clean-cut perforations at all stages of the operation upon all portions of the paper or other material passing through the perforating means. Difficulty has been experienced because of the necessary slowness of the operation, in the past, as well as in its imperfection. For these reasons the reciprocating plunger type of perforating means has been found difficult of operation, but has been used, of necessity, in the art. My invention obviates the difficulties of that mechanism, namely, the difficulty of securing the paper to lie flat upon the bed over which it was passed and by which it was sustained during the punching operation, the difficulty of feed, the difficulty of slowness and the difficulty of securing clean cut perforations.

An attempt to use rolls has met with objection because of the fact that positioning of the punching means on rolls was difficult to make in any way, and because driving the rolls in unison has heretofore been found impossible in the practical working of the art. My invention provides a means both for positioning of the rolls one to the other and in relation to the paper, and my invention also provides a means whereby the relative movement of the rolls is harmoniously secured with a result that the paper is fed, punched and discharged with great speed, with perfect perforation, and in uncrumpled condition.

Another object of my invention is to provide a means of adjustment of the rolls rela-

tive one to the other so that the adjustment can be rapidly and unerringly made by the operator, yet with no danger of mistake in registering the pins with the holes, thus obviating the former difficulty which has prohibited the use of such means because any such attempt has failed through the shearing of the pins when the mechanism was started, due to imperfect register and other causes.

It is an object of this invention to furnish a mechanism comprising a pair of rotating drums provided with coöperating means for perforating the paper or other medium. It is also an object of this invention to so relate these rotating drums as that one shall operate the other, so that their intersection in performing the perforating function shall be accurate and harmonious. With such an adjustment of the drums as to correctly position them, the performance of rapid and accurate work is possible in the perforation of paper or other medium of varying widths, varying thicknesses, and a varying arrangement of perforations upon a punching bed where the paper can lie perfectly even and flat without wrinkling, crumpling or tearing.

In the accompanying drawings, Figure 1 is a front elevation of the mechanism, partly in section; Fig. 2 is a side elevation looking toward the left in Fig. 1; Fig. 3 is a section on the line 3 3 of Fig. 1, looking in the direction of the arrows; Fig. 4 is a section on the line 4 4 of Fig. 3, looking in the direction of the arrows; and Fig. 5 represents the sheet as perforated by the machine.

In the embodiment of the invention here shown the machine comprises a pair of parallel frame members 1 and 2 having slots 3 and 4 therein, respectively. Mounted in the upper portions of said slots is a pair of bearing blocks 5 and 6. These bearing blocks are held in place upon the frame members by means of face plates 7 and 8 provided with suitable fastening devices 9 and 10, respectively. Rotatably mounted within these bearing blocks is a shaft 11 having reduced end portions 12 and 12' located within the bearing blocks. The shaft 11 may be driven in any suitable manner from any source of power, but as here shown, is provided with a gear 13 at one end thereof in mesh with a chain of gears 14, 15 and 16 which are driven from the printing press, the latter not being

shown. Mounted below the bearing blocks 5 and 6 are the adjustable bearing blocks 17 and 18. These bearing blocks are held against movement transversely of the slot by 5 means of the face plates 19 and 20, respectively, which are fastened to the respective bearing blocks by means of suitable fastening devices 21 and 22. The frame member 1 is provided below the bearing block 17 with 10 a screw-threaded socket 23 in which is located a screw 24 having a head 25 in engagement with the lower end of the block to adjustably support the same. This head 25 may be adjusted in any suitable manner to 15 raise and lower the block 17. This screw is locked in position by means of a locking nut 26. In a like manner the frame 2 is provided with a screw-threaded socket 27 having a screw 28 mounted therein, the screw 20 28 having a suitable head 29 in engagement with the bearing block 18. The screw 28 is locked by means of a nut 30. A shaft 31 having reduced end portions 32 and 32' is journaled in these bearing blocks 17 and 18. 25 By the arrangement above described the shaft 31 can be adjusted vertically, while the shaft 11 is fixed relatively to the frame.

Mounted upon the shaft 11 is a series of drums 33 and 34. The drums 33 are single 30 drums, while the drums 34 are double drums, that is, the drums 33 have a single series of perforating devices, while the drums 34 have a double series of perforating devices. These drums are keyed to the shaft 11 to rotate 35 therewith by means of a suitable key 35. They are, however, adjustable longitudinally of the shaft and may be held in any longitudinal position by means of set screws 36. Mounted upon the shaft 31 is a series of 40 drums 37 and 38 adapted to coöperate with the drums 33 and 34. The drums 37 have a single series of holes therein, while the drums 38 have a double series of holes there- 45 in corresponding to the drums 33 and 34. The drums upon the shaft 31 may be adjustably rotated around the shaft and also adjusted longitudinally thereof and held in place thereon by means of set screws 39.

In the manufacture of paper for use in 50 manifolding machines it is usual to have what is known as the original web and two duplicate webs of perforated paper. These webs are all made in one piece and are later cut to form three webs. It is for this reason that the machine above described consists of two double rolls and a pair of single rolls at each side thereof. The paper after passing through the rolls appears as shown 55 in Fig. 5. It will be understood that a single 60 pair of coöoperating drums may be used or more, according to the width of the strip to be perforated and the number of rows of perforations required.

The drums 33 are provided with a single 65 series of sockets such as is indicated at 40 in

Fig. 4. The drums 34 are provided with a double series of like sockets. Within each socket is a cylindrical pin 41 having a projecting flat blunt end, as indicated at 42. The inner portion of the pin 41 is notched, 70 as shown at 43, and is held in place within the socket 40 by a wedging engagement with the screw 44. By the arrangement above set forth the pins as they wear can be easily replaced and when in use are held rigidly 75 upon the drums. The drums 37 and 38 are hollow, as shown at 45. Each drum 37 comprises a single series of radial holes and each drum 38 comprises a double series of such holes, as indicated at 46 in Fig. 4. One 80 end of each hole 46 communicates with the circumference of its drum and a pin 41 is adapted to mesh therewith, as shown. The opposite ends of the holes open into the hollow portions 45, whereby the paper cut 85 out to form the perforations may escape away from the machine. The portions of the drums 37 and 38 in which the holes 46 are located must be of very hard material, as the wear and tear upon the sockets and pins 90 is very great. As shown in Fig. 1, these drums are provided in sections, whereby portions may be replaced if necessary.

As shown in Fig. 2, the paper after being printed is fed around the roll 47 upon 95 which the gear 16 is mounted, around the idler 48, and across the idlers 49 and 50. The idlers 49 and 50 are so located with reference to the drums upon the shafts 11 and 31 that the paper will pass between the said 100 drums substantially tangentially thereto. After passing around the idler 50 the web of paper is rewound by any suitable mechanism, but preferably by mechanism timed to 105 rewind the paper at a rate proportionate to the rate of rotation of the drums which feed the web.

It will be seen that I have provided drums upon the shaft 11 which may be adjusted longitudinally to vary the distance between 110 the successive rows of perforations. It will also be seen that the drums 37 and 38 can be adjusted longitudinally of the shaft 31 to properly engage the drums 33 and 34 in accordance with the adjustment of these 115 last-mentioned drums. Furthermore, the drums 37 and 38 can be adjusted vertically to properly position these drums relatively to the upper drums in order to cause a correct meshing to produce the best results. 120 The drums 37 and 38 can also be rotated around the shaft 31 to properly adjust the holes with reference to the pins. It will be seen that the drive is connected entirely 125 to the upper shaft 11 and that the drums 37 and 38 and the shaft 31 are rotated through the instrumentality of the upper drums. The mechanism above described has a wide range of adjustment by which the 130 perforations are made clean cut and tear-

ing is prevented. The web of paper is fed at substantially right angles or tangentially between the rolls and the cylindrical projections upon the rolls 33 and 34 so mesh 5 with the cylindrical holes in the lower rolls that the cutting is very perfect and tearing of the paper is prevented.

The mechanism above described is especially adapted for use in connection with printing presses and by means of the gearing 13, 14 and 15 a positive and steady drive is obtained and the rotation of the drums 33, 34, 37 and 38 synchronizes with the operation of the printing press in a proper manner. Furthermore, the web of paper is fed by means of this properly timed mechanism from the printing press, although the mechanism can be operated entirely independently of a printing press, if so desired. 20 The pins 41, it will be noticed, can be removed as they become worn and are held in place by a driving fit within the sockets 40, the notched portion 43 forming an inclined surface which wedges the pins securely in 25 place against the screw 44.

In the operation of the mechanism the drums 33 and 34 are rotated and the cylindrical projections thereon enter the holes upon the lower drum forming a perforation 10 in the web of paper, the piece of paper from the perforation passing out through the hollow portion 45.

While I have shown and described one embodiment of my invention it will be understood that this has been chosen for the purposes of illustration only, and that I do not desire to be limited to the details of construction shown and described, for obvious modifications will occur to a person 5 skilled in the art.

Having thus fully described my inven-

tion, what I claim as new and desire to secure by Letters Patent, is:—

1. In a perforating machine, the combination, with a driving shaft, of a drum 45 mounted fast thereon, punches carried on the periphery of said drum, a second shaft, a drum adjustably mounted thereon and having die holes in its periphery corresponding to and engaged by the punches 50 on said first drum, a gear having a paper feeding roller fast thereto, connections from said gear to said first drum constructed to feed the paper at the same velocity as that of the punches, and means for carrying the 55 paper tangentially between the two drums.

2. In a perforating machine, the combination, with a driving shaft, of a drum mounted fast thereon, punches carried on the periphery of said drum, a second shaft, 60 a drum adjustably mounted on said second shaft and having die holes in its periphery corresponding to and engaged by the punches, means for adjusting said second shaft toward and away from the first shaft, 65 a gear having a paper feeding roller fast thereto, connections whereby said gear drives said punch drum at the same speed as the paper is fed, and idle rollers over which the paper passes and positioned to 70 cause the paper to move tangentially between the two drums.

3. In a perforating machine a holding element, a pin having an inclined notched portion with the wide portion of the notch at 75 the inner end of said pin, and means cooperating with the inclined portion for fixing the pin in a socket in said holding element and wedging the same when an upward thrust is exerted thereon.

In testimony whereof, I affix my signature.
AXEL C. V. MALM.
